UNITED STATES PATENT OFFICE

1,938,026

CAR DOOR OPENER

Elwin H. Kidder, Chicago, Ill., assignor to Link-Belt Company, Chicago, Ill., a corporation of Illinois

Application June 1, 1931. Serial No. 541,381

14 Claims. (Cl. 214—54)

My invention relates to a grain car unloader and has for one purpose the provision of unloading means whereby a car filled with grain can quickly and efficiently be unloaded. Another purpose is the provision of door opening means for such a grain car unloader and, particularly, door opening means which will operate, when the grain car is tilted laterally, to press in the car door and to permit the grain to escape. Another object is the provision of means for holding the grain car door out of the line of grain flow after it has been opened. Other objects will appear from time to time in the course of the specification and claims.

I illustrate my invention more or less diagrammatically in the accompanying drawings, wherein—

Figure 1 is a side elevation;

Figure 2 is an end elevation of the parts prior to the car door being opened;

Figure 3 is an end elevation with parts in section, illustrating the opening device in position at the end of the grain car door opening movement.

Figure 4 is a partial top plan view of one side of the platform structure and associated parts;

Figure 5 is an enlarged section along the line 5—5 of Figure 1; and

Figure 6 is a section along the line 6—6 of Figure 5.

Like parts are indicated by like symbols throughout the specification and drawings.

Referring to the drawings, A generally indicates the bottom of any suitable pit, provided with walls A¹. A² indicates a projection or bracket extending inwardly from one of said walls upon which some of the car handling mechanism below described may be positioned. A³ generally indicates a receiving hopper with the bottom A⁴ and the discharge apertures A⁵ which may be closed as by any suitable removable closure members A⁶. A⁷ indicates a conveyor belt upon which the grain discharged through the apertures A⁵ may be received and conveyed for disposal elsewhere.

B B indicate base members herein shown as positioned upon the bottom A of the pit, and supporting any suitable frame B¹. B² indicates any suitable motor, for example an electric motor which drives a gear train including the motor shaft pinion B⁶, the gear B⁷. Associated with the gear B⁷ is any suitable drum B⁸ about which pass the cables B⁹ B⁹.

C C indicate rollers, pivoted upon the frame B¹. These are channelled as at C¹ to receive the

arcuate track C². This track is mounted upon any suitable supporting framework generally indicated as C³, upon which in turn is mounted any suitable platform structure C⁴ which may have positioned upon its top the track rails C⁵. 60 The cables B⁹ are dead ended or secured, at their ends, at opposite ends of the tracks C², as at C⁶ C⁶, for example in stop members C⁷ which serve, by contact with the rollers C, to limit the possible tilt of the platform or cradle structure 65 above described. It will be understood that when the cradle or platform is in the position in which it is shown in Figures 2 and 4, the ends of the platform C⁵ are positively supported. I indicate for example supporting abutments C⁶ 70 for the left side of each end of the platform, and supporting abutments C⁷ for the right side of each end of the platform, the supporting abutments C⁷ being farther from the mid point of the platform than the abutments C⁶, the platform 75 being forwardly extended as at C⁸, in order to engage and rest upon the abutments C⁷. It will therefore be understood that when the parts are in the position in which they are shown in Figures 2 and 4, any longitudinal tilting of the platform is positively prevented by the abutments 80 upon which it rests, and with which, in effect, the platform interlocks. As shown in Figure 2 it will be noted that the abutments C⁶ are provided 85 with convex upper surfaces which rest in corresponding concave surfaces C⁹ of the blocks C¹⁰ upon the lower portion of the ends of the frame.

D D indicate any suitable clamps for the ends of the car generally indicated as D¹ and positioned, when inoperative, in the pits D¹¹. They 90 may include pads or abutment members D² opposed to the couplings D³ of the car, and any suitable means may be employed for raising and drawing the clamps D into operative position when it is desired to secure a car in place 95 upon the platform. As the details of the clamping mechanism do not of themselves form part of the present invention, they are diagrammatically illustrated. I may for example employ a motor D⁴ mounted on the platform C⁴ which drives the shaft D⁶ through the gear reductions generally indicated as D⁵. The shaft D⁶, through the gear reductions D⁷, drives the nut D²⁰ which moves the screw D⁸ longitudinally. D⁹ indicate 100 tracks along which the carriages D¹⁰ may move into and out of operating position for the conveyance of the clamps D into and out of operative position.

Extending upwardly from one side of the plat- 110

form C⁴ is a bracket frame E which supports an upstanding frame structure generally indicated as E¹, which includes the transverse top structural member E². Pivoted adjacent or upon the transverse member E² is a hanger structure indicated as E³, which may be pivoted as at E⁴. At its lower end is a guide E⁵ upon which is adjustably or slidably mounted the door engaging member E⁶, which may for example have a plate provided with 5 the forward spikes or projections E⁷. Any suitable means may be employed for raising and lowering the door contacting member E⁶. I may employ for example the cable E⁸ passing about a sheave E⁹ and about a shaft E¹⁰, the rotation of 10 which may be controlled as by the lever E¹¹ and ratchet wheel E¹² and the dogs E¹³, E¹⁴. The dog E¹³ is mounted on the lever E¹¹ and serves to rotate the ratchet, while the dog E¹⁴ is mounted on 15 the hanger and serves to prevent unintended retrograde rotation of the ratchet. However, any other suitable means for raising or lowering the member E⁶ may be employed.

Mounted on the platform A² is the unitary frame G upon which is mounted any suitable motor G¹ which drives, through its motor shaft pinion G², a gear G³ upon the shaft G⁴, the pinion G⁵ of which is in mesh with a gear G⁶ which is mounted on a threaded sleeve G⁷, the rotation of 20 which actuates the screw G⁸, to impart longitudinal or axial movement thereto. G⁹ generally indicates a universal joint or universal coupling for the opposite end of the screw G⁸. I do not wish to be limited to any specific universal joint, but I have shown a block G¹⁰ on the end of the screw G⁸ to which is pivoted a yoke G¹¹ to which in turn is pivoted another yoke G¹², which in turn is connected to a rod G¹³ which is connected by a similar universal connection at its opposite end to the 25 upright frame structure E¹, as upon the horizontal longitudinal plate E¹⁴. It will be understood that as the motor G¹ is actuated the rotation of the sleeve G⁷ imparts axial longitudinal movement to the screw G⁸ and thus moves the platform or cradle structure as a whole toward or away from the bracket A². It will be understood that the car dumper platform C⁴ is supported upon the track C² which in turn is supported upon the rollers C, seating in the grooves C¹ of said rollers. It will be seen, as in Figures 2 and 3, that when the rails 30 C⁵ on the platform C⁴ are aligned with the rails C²⁰ of the track ends, the frame structure C³ is tilted to the left, referring to the position of the parts as in Figure 2, and that the weight of the structure thus tends to hold the platform C⁴ firmly 35 in position upon the supporting abutments C⁶. Any additional locking means may be employed if desired, but the structure is normally gravitally held in position. On the other hand, when it is desired to tilt the car longitudinally and the parts are moved into the position in which they are 40 shown in Figure 3, the frame structure C³ lies in a generally vertical plane.

H indicates any suitable deflector whereby grain discharged from the car D¹ may be delivered into the bin A³.

It will be understood that it is current practice to nail inner grain car doors within the normal doors of the freight cars in which grain is shipped. The permanent freight car doors, 45 which are not indicated herein, being slid or moved out of alignment with the door opening, there are still left the boards J of the grain door, which may for example be nailed at the inside of the door aperture. When the car is tilted laterally into the position in which it is shown in

Figure 3, the members E⁶ and E⁷ must be moved forwardly against the grain door. In order to effect this movement I provide a compression member J¹ which is connected at one end, by means of a universal joint J² to the hanger structure E³. At its other end it is connected as by the universal connection J³ with any suitable cover or housing J⁴ which forms part of or is secured to the unitary structure generally indicated as G. It will therefore be understood that as the car structure is tilted laterally to the position of Figure 3, the member J¹ serves as a compression member to prevent the complete unitary movement of the members E⁶ and E⁷ with the car. As the car and car support C⁴ tilt, the hanger E³ is forced to pivot about its axis E⁴. This first engages the member E⁶ with the door boards J, and then forces them into the position shown in Figure 3. Points E⁷ normally hold the door boards J in place as a unit and entirely out of alignment with the escaping grain.

In the operation of the device a car is first spotted on the platform C⁴. The clamps D are then actuated to hold it in place. The motor G¹ is then actuated to draw in on the member G³ which then serves as a tension member to tilt the frame C³ and the platform C⁴ laterally about a pivot defined by the rollers C. However, this lateral tilting movement causes the member J¹ to serve as a compression member and to force the door boards J into the position in which they are shown in Figure 3 as above described. The motor B² may then be actuated to tilt the car longitudinally, and the grain pours out through the car door and upon the deflector H and into the bin A³. Any suitable means may be employed for assisting the escape of the grain, such as baffles or the like, such means not herein indicated as not forming of themselves part of the present invention. When the car has been finally cleared of its grain it may then be rotated back to the position in which it is shown in Figure 1 with the result that the door opener is also returned to the position in which it is shown in Figure 1. The clamps D can then be moved into inoperative position and the car removed along the rails C²⁰.

It will be realized that whereas I have described and shown a practical and operative device, nevertheless many changes may be made in size, shape, number and disposition of parts without departing from the spirit of my invention. I therefore wish the drawings and description to be taken as in a broad sense illustrative or diagrammatic rather than as limiting me to my specific showing herein.

Because the door opening foot is supported on a stiff pendent link which is pivoted about a horizontal axis above the car floor, which axis moves toward and from the fixed abutment as the car and cradle tilts, and because there is a positive connection between the fixed abutment and the car door opening foot, it will be seen that tilting movement of the car and cradle not merely pushes the grain car door in, but also rotates it about an axis perpendicular to the plane of movement of the car as it tilts sideways and so gives the car door a movement inwardly into the car along an arcuate path, thereby positively raising the car door out of line with the flow of the grain and insuring that the movement of the car door will be positively controlled at all times and will from its inception be in a direction inclined to the direction of tilting movement of the car and to the floor of the car at all times.

It will also be noted that because the cradle and car is supported positively by the abutments at the ends of the cradle, and because the lower ring or keel which supports the cradle on the two lower supporting rollers is inclined downwardly and forwardly in the direction of tilt, the effect of the tilting means, pulling the car and cradle over to bring the lower ring almost into a vertical position, tends to raise the car against gravity so that the tilting movement is positively imparted by the operating mechanism, independent of the weight or character of the burden in the car. This raising movement of the car off its abutment, combined with a part of the lateral tilting movement, makes especially important the rotary movement of the car door opener which tends to lift the door more rapidly away from the original plane of the car floor than the car floor itself is lifted above its original plane by the tilting mechanism.

It will also be noted that the axes about which the whole structure rotates for endwise tilt is substantially on line with the fixed abutment so that the universal joint connection between the threaded sleeve on the abutment and the cradle is sufficient to permit the endwise tilt of the cradle and car without interference.

Moreover, since the thrust member interposed between the fixed abutment and the lower end of the door opening link is substantially parallel with and very close to the tilting connection, the universal joint connections associated with the thrust member permit endwise tilt to take place without disturbing the relation between the car door opener and the fixed abutment, and the fact that the car door opening foot is held up at a relatively slight slope enables it to support and hold the door way above the line of grain flow during or succeeding tilting movements, and the door is released and dropped into the car adjacent to the door opening only after the car has been emptied of grain and has returned to a position whence it can be moved off of the cradle.

I claim:

1. In a car unloader, a cradle, means for positioning a car thereupon, an abutment positioned adjacent said car and cradle, a car door opener movably mounted upon said cradle and including a portion adapted to be opposed to a door positioned in the side of said car, and thrust means permanently connected at one end to said abutment and at the other end to the door opener; said thrust means being adapted in response to lateral movement of the car toward said abutment, to move said door opener inwardly against the car door, and means for laterally moving the car and cradle toward and away from said abutment, and a universal joint associated with the thrust means.

2. In a car unloader, a cradle, means for positioning a car thereupon, an abutment positioned adjacent said car and cradle, a car door opener pivoted upon said cradle, said pivot moving with said cradle and being normally fixed in relation to the cradle and car, said car door opener including a portion aligned with a door positioned on the side of the car, and thrust means permanently connecting said car door opener to said abutment, adapted in response to lateral movement of the car toward the abutment, to move said car door opener inwardly in relation to the car door, and adapted, in response to lateral movement of the car away from said abutment, to positively withdraw the door opener in rela-

tion to the car door, and means for longitudinally tilting the car and cradle about an axis adjacent the location of said thrust means.

3. In a car unloader, a cradle, means for positioning a car thereupon, an abutment positioned adjacent said car and cradle, a car door opener movably mounted upon said cradle and including a portion adapted to be opposed to a door positioned in the side of said car, and thrust means permanently connected at one end to said abutment and at the other end to the door opener, said thrust means being adapted, in response to lateral movement of the car toward said abutment, to move said door opener inwardly against the car door, and means for laterally moving the car and cradle toward and away from said abutment, and means for longitudinally tilting the car and cradle about an axis adjacent the location of said thrust means.

4. In a car unloader, a cradle, means for positioning a car thereupon, said cradle being laterally movable, means for supporting said cradle, effective when it has been laterally moved, which includes an arcuate edged supporting member, a bracket associated with the cradle and moving therewith, extending upwardly adjacent the side of the car toward which the cradle moves, a door removing member movably mounted on said bracket, a thrust connection element associated with said door removing member and an actuating element for imparting lateral movement to the cradle as a whole, said two elements being both positioned adjacent the center about which the arcuate edge of the support is described.

5. In a car unloader, a cradle, means for positioning a car thereupon, said cradle being laterally movable, means for supporting said cradle, effective when it has been laterally moved, which includes an arcuate edged supporting member, a bracket associated with the cradle and moving therewith, extending upwardly adjacent the side of the car toward which the cradle moves, a door removing member movably mounted on said bracket, a thrust connection element associated with said door removing member and an actuating element for imparting lateral movement to the cradle as a whole, said two elements being both positioned adjacent the center about which the arcuate edge of the support is described, and a normally fixed base, adjacent the cradle, upon which the outer ends of said members may be mounted.

6. In a car unloader, a cradle, means for positioning a car thereupon, said cradle being laterally movable, means for supporting said cradle, effective when it has been laterally moved, which includes an arcuate edged supporting member, a bracket associated with the cradle and moving therewith, extending upwardly adjacent the side of the car toward which the cradle moves, a door removing member movably mounted on said bracket, a thrust connection element associated with said door removing member and an actuating element for imparting lateral movement to the cradle as a whole, said two elements being both positioned adjacent the center about which the arcuate edge of the support is described, and a normally fixed base, adjacent the cradle, upon which the outer ends of said members may be mounted, said members being flexibly connected at one end to said base and flexibly connected at the other end to the cradle and to the car door removing means respectively.

7. In a car unloader, a cradle, means for tilt-

- ing it longitudinally, a door opener comprising a door engaging member, a pivot link supporting it, the axis of rotation of the pivot link being fixed with respect to the cradle and constrained to rotate both laterally and longitudinally with it, the axis of rotation of the link being parallel with the longitudinal axis of the car, means for moving the cradle laterally, said means being applied to the cradle at a point adjacent the car door, a thrust member fixed at one end with relation to the cradle tilting means and pivoted at the other end on the door opener link, the link being located adjacent the means for moving the cradle laterally, and above the door opening thrust member, said cradle moving member including universal joint means whereby longitudinal tilting of the cradle may take place without interfering with the operation of said link. 5
8. In a car unloader, a cradle mounted for lateral and longitudinal tilting, a car door opening means mounted on the cradle, adapted to swing toward and from the car, a fixed abutment at one side of the cradle, means associated with the abutment and connected to the cradle at a point adjacent the center of longitudinal tilting, for drawing the cradle toward the abutment, a thrust member mounted on the abutment and interposed between the abutment and the car door opening member, and universal joint means associated with the thrust member and the tilting link, whereby longitudinal rotation of the cradle may take place without interfering with their operation. 10
9. In combination with a car dumper cradle adapted for lateral movement and for longitudinal tilting, a door opener movably supported on the cradle, a fixed abutment adjacent the cradle and a permanent connection between the abutment and the door opener whereby movement of the cradle causes movement of the door opener with respect to its support on the cradle, the connection between the abutment and the door opener being continuously operative to maintain the door opener in position independent of the longitudinal tilting of the cradle. 15
10. In combination with a car dumper cradle adapted for lateral movement and for longitudinal tilting, a door opener pivotally supported on the cradle, a fixed abutment adjacent the cradle and a permanent connection between the abutment and the door opener whereby movement of the cradle causes angular movement of the door opener about its pivot support on the cradle, the connection between the abutment and the door opener being continuously operative to maintain 20
- the door opener in position independent of the longitudinal tilting of the cradle. 11. In combination with a car dumper cradle adapted to tilt laterally and longitudinally, a door opener pivotally supported on the cradle, a fixed abutment adjacent the cradle and a permanent connection between the abutment and the door opener whereby tilting of the cradle causes angular movement of the door opener about its support on the cradle, the connection between the abutment and the door opener being continuously operative to maintain the door opener in position independent of the longitudinal tilting of the cradle. 25
12. In combination with a car dumper cradle adapted to tilt laterally and longitudinally, a door opener movably supported on the cradle, a fixed abutment adjacent the cradle and a permanent connection between the abutment and the door opener whereby tilting of the cradle causes movement of the door opener with respect to its support on the cradle, the connection between the abutment and the door opener being continuously operative to maintain the door opener in position independent of the longitudinal tilting of the cradle. 30
13. In combination with a car dumper, a cradle mounted to tilt both laterally and longitudinally and adapted to support a grain car, a door opener mounted permanently in line with the side door in the grain car, means responsive to the lateral tilting of the car for forcing the door inwardly against the weight of material in the car and for imparting to the door a rotary movement about an axis generally parallel with the longitudinal axis of the car whereby the door may be rotated inwardly and upwardly above the flow line of material in the car, the means for forcing the door inwardly comprising a pressure member which remains in fixed working relation with the door opener independent of the longitudinal tilt of the cradle. 35
14. In combination with a car dumper having a cradle mounted to tilt both laterally and longitudinally and adapted to support a grain car, a door opener pivoted on the cradle and adapted to swing toward and from the car door, a fixed abutment, a thrust connection between the abutment and the door opener whereby lateral tilting of the cradle toward the abutment opens the door of the car by thrusting the door opener inwardly into the car, the connection being operative independent of the longitudinal tilting of the car and cradle to maintain positive control of the door throughout the entire dumping action. 40
